UNITED STATES PATENT OFFICE.

JOHN HEBERLING, OF ROCHESTER, NEW YORK.

PINWHEEL.

Application filed February 27, 1925. Serial No. 12,118.

The object of this invention is to make a new and improved form of toy comprising a pinwheel turning a crank and driving a toy object which toy can be made cheaply and sold cheaply and in large quantities to correspond. This and other objects of the invention will be illustrated in the drawings, described in the specification and pointed out in the claims at the end thereof.

10 In the drawings:

Figure 1 shows a front elevation of my improved wheel and toy.

Figure 1^A is a detail of the platform on which the toy figure is mounted.

15 Figure 2 shows a side elevation thereof.

Figure 3 is a perspective view of the crank which is attached to the wheel and turns on the stationary supporting shaft to drive the figure.

20 Figure 4 is a detailed view of one of the blades or sections of which the wheel may be made.

Figure 5 is a perspective view of the metal disc having lugs thereon for clamping the 25 sections of the wheel together, said disc having a crank for driving the object.

Figure 6 is a front elevation of the toy in which a pinwheel made of a single piece is used.

30 Figure 7 is a front elevation of a modified form of my pinwheel.

Figure 8 shows a side elevation of the toy shown in Figure 7.

Figure 9 is a perspective view of the metal 35 crank mounted on the pinwheel and used to drive the toy.

Figure 10 is a perspective view of a modified form of the platform and the figure attached thereto, one part of which figure is 40 made integral with the platform.

Figure 11 is a modified form of the toy in which the figure of a clown is rocked by the turning of the pinwheel.

Figure 12 is a view of the modified form 45 of the toy in which the figure of a horse is rocked by the turning of the pinwheel.

In the drawings like reference numerals indicate like parts.

50 In the drawings reference numeral 1 indicates the stick upon which the toy is mounted. 2 indicates a pin or shaft which is fastened rigidly in the stick. 3 indicates the wheel that turns on the shaft which may be made of a single blank such as is shown in Figure 6, or may be made of a plurality

of sections or blades 4 such as is shown in Figure 4, each of these sections may be made of a different sheet of material such as celluloid, each of which sheets may be of a different color, so that the wheel presents a 60 more brilliant appearance. Fastened to this wheel is a wire bracket 5 having a hook 6 on one end thereof that passes through the pinwheel and positively engages therewith so that it is positively turned thereby. It 65 also has an eye 7 formed therein which encircles the shaft 2 and on the other end thereof is formed a crank 8. When assembled on the wheel, the long arm and hook 6 serve to counterbalance the crank 8 and 70 the parts connected therewith, so that the wheel turns readily and easily and freely to drive the toy figure associated with it. When the wheel is made of three sections similar to that shown in Figure 4, the hubs 75 of each section are perforated at three places so that when assembled, the three lugs on the plate 9 will pass therethrough to clamp the hubs of the sections together. This plate has a crank 10^A thereon to turn 80 the figure and a counter-balance 10^B for said crank.

Mounted on the same stick below the shaft 2 is provided a platform 10 on the front of which platform is rigidly fastened the support 11 of the body of a man. This support comprises the hips and legs of the body. At 12 is pivotally mounted on this support the part 13 which comprises the torso and head of the figure. Pivotally mounted on 85 the torso at 14 is the arm 15 the forward end of which pivotally engages with the crank 8 on the pinwheel.

It is obvious that the bracket 5 may be fastened to either side of the wheel, that is 90 either front or back, but the arrangement as shown in Figures 1 and 2 and 6 is the more desirable because the figure does not intercept the wind before it engages with the wheel so that the wheel is driven to the 95 best advantage and turns the figure to the best advantage. It will also be understood that the platform 10 is shown made of a block of wood which is perforated in one corner to receive the stick 1 and make a rigid engagement therewith, and to the front face of this block the support 11 is rigidly fastened. A detail of this block is shown in Figure 1^A.

In Figure 7 I have shown a modified form 110

of the wheel in which the stick 1, pin or supporting shaft 2 and the pinwheel 3 are used similar to what has been above described. To the wheel 3 in this instance is 5 fastened a metal bracket 20 having a pin hole 21 therein and an arm 22 bent up therefrom. This arm engages the wheel in the depression as shown at 23 so that it is positively turned thereby. The lower end of 10 the bracket is bent up into the crank 24 having a reduced end 25 at the end thereof the end of which is upturned as shown at 26 to hold the crank in engagement with the arm 27 of the toy figure driven by the 15 wheel.

Below the shaft the stick 1 carries a sheet metal platform 28 which is perforated at 29 to form a hole and socket to receive the stick on the forward end. The metal is 20 slit and bent up at the opening to form a flange around the opening to steady it on the stick. This platform has lugs thereon that pass through the card 30 and are bent up and down to make a positive engagement 25 therewith to hold the card rigidly to the platform. The torso 31 is pivotally mounted on the card 30 and the arm 27 is pivotally mounted on the torso 31. When the pinwheel 3 turns it carries the crank 24 with it and this in turn causes the figure to rock back and forth on the turning of the wheel.

In Figure 10 I have shown a modification of the toy in which a metal platform 35 is used, one end of which is bent U-shaped 35 and is provided with perforations 36 and 37 to receive the stick 1 which supports the toy. The outer end of the platform is bent up as shown at 38 to form the lower part 40 of the figure. The upper part of the figure 13 is mounted thereon the same as is shown in Figures 1 and 6.

In Figure 11 I have shown a modification of a pinwheel in which 3 indicates the wheel partly broken away, 5 indicates the bracket 45 and 40 indicates the link attached to the crank thereof, which link is attached to an arm of a clown 41 which clown is pivoted at 42 on a bracket 43 on which it rocks on the turning of the wheel.

In Figure 12 I have shown another modification of the toy in which 3 represents the wheel partly broken away having the bracket and link as above described, the lower end of the link being attached to a 55 horse 45 which is pivoted at 46 to rock on a bracket 47 so that as the wheel turns the horse rocks.

I claim:

1. The combination of a pinwheel, mounted 60 on a stationary shaft, a support for said shaft on one end thereof, a crank fastened to said wheel on the side opposite to said support, and rotating therewith around its axis, a second support joined to 65 said first support, a figure pivotally mounted

ed on said second support adjacent to said wheel and connected to said crank whereby on the turning of the pinwheel the figure is rocked back and forth thereby.

2. The combination of a stick, a shaft 70 mounted stationary thereon, a pinwheel adapted to rotate on said shaft, a crank fastened on said wheel on the end opposite to said stick and rotating therewith around its axis, a platform having a hole therein through which the stick passes and by which it is attached to said stick and said platform extending out therefrom below the shaft, a figure having its lower end attached rigidly to said platform making its legs stationary, said figure having its body pivoted on the legs thereof and having an arm pivoted on said body, the forward end of said arm being pivoted on said crank, whereby on the turning of the wheel the 85 figure is rocked back and forth thereby simulating the movement of a person turning a wheel by a crank.

3. In a pinwheel toy, the combination of a pinwheel, a stationary shaft on which it 90 is adapted to turn, a bracket having an eye therein adapted to embrace and turn around said shaft, one end of said bracket being turned in to engage with said wheel, the other end of said bracket being turned out 95 to form a crank.

4. A wind wheel toy comprising a stem, a shaft extending laterally from the stem, a wind wheel turning on the shaft, a bracket extending laterally from the stem, a pivoted member mounted to oscillate on the bracket, a link pivoted eccentric to the pivoted member, and a sheet metal member fastened to the wind wheel and bent to provide two arms extending laterally therefrom in opposite directions, one of said arms projecting between the blades of the wind wheel and the other having the link pivoted thereon.

5. A wind wheel toy comprising a stem, 110 a shaft extending laterally from the stem, a wind wheel turning on the shaft, a bracket extending laterally from the stem, a pivoted member mounted to oscillate on the bracket, a link pivoted eccentric to the pivoted member, and a metal member fastened to the wind wheel and bent to provide two arms extending laterally therefrom in opposite directions, one of said arms positively engaging the wind wheel and the 115 other having the link pivoted thereon.

6. In a pin wheel, a series of blades each of said blades being individual and cut as a blank separate from the remaining blades, each blade having a hub with a perforation 125 therein, the hubs of said blades overlapping each other with the perforations of the hubs in line with each other, means for fastening said hubs together and suitably spacing said blades apart, each of said blades hav-

ing a perforated tip, which tips are curved over the hubs and are held together in front of it to conceal it.

7. In a pin wheel, a series of blades each made of a separate blank, each blank having a perforated hub, the hubs of said blades overlapping each other with the perforations of the hubs in line with each other, means for fastening said hubs together and 10 suitably spacing said blades apart, one of the tips of each of the blades having a perforation therein, said tips overlapping and concealing the hub.

8. A pin wheel comprising a series of 15 blanks, each having a hub section formed at one end thereof, said hub sections being adapted to overlap one another and means

for clamping said hub sections on top of one another and lock them against radial movement with relation to each other. 20

9. A pin wheel comprising a series of blanks, each having a hub section formed at one end thereof, said hub sections being adapted to overlap one another and means 25 for clamping said hub sections on top of one another and lock them against radial movement with relation to each other, the free end of said series of blanks being adapted to be curved over in front of said hub section and held parallel to their corresponding hub section. 30

In testimony whereof I affix my signature.

JOHN HEBERLING.
